United States Patent Office.

DAVID M. BUCKLEY, OF ATHENS, OHIO.

Letters Patent No. 76,990, dated April 21, 1868.

IMPROVED CLOTHES-DRIER.

The Schedule referred to in these Letters Patent and making part of the same.

TO ALL WHOM IT MAY CONCERN:

Be it known that I, DAVID M. BUCKLEY, of Athens, in the county of Athens, and State of Ohio, have invented a new and useful Improvement in Clothes-Driers; and I do hereby declare that the following is a full, clear, and exact description of the same, reference being had to the annexed drawings, making part of this specification.

The frame A supports the shaft B, turning on journals supported on the frame. The shaft may be turned by a winch, C, provided with a ratchet, to prevent the shaft from turning in the direction in which the cords are unwound. These cords or straps, D, are attached to the shaft, so that they may be wound around it by turning the winch. One of the cords is placed near each end of the shaft. At suitable spaces along the parallel cords are attached horizontal bars, E F.

Cords or straps, E E, are attached to the sides of cords D, at about their own length above the bars F. To the lower ends of these short cords, E, are fastened bars, F', arranged on each side of the bars F. These bars are, when required for use, held at a suitable distance from the bars F, by means of the brace-rods G G, extending from the bar F to the parallel bar F'. By this means, three parallel rods are placed, at suitable intervals, parallel with one another, upon which clothes may be suspended. Other series may be added outside of these, if required.

The cords D and supported bars may be wound around the shaft B, and only so much of the same uncoiled as may be required for use.

What I claim as my invention, and desire to secure by Letters Patent, is—

A clothes-drier, constructed with a shaft, B, cords D and E, and parallel bars F F', arranged substantially as described.

In testimony whereof, I have signed my name to this specification in the presence of two subscribing witnesses.
